DESIGN FOR AN ELECTRIC BARBECUE
ROASTER OR SIMILAR ARTICLE

Jules Nisenson, New York, N. Y.

Application July 29, 1946, Serial No. 132,081

Term of patent 14 years

(Cl. D81—10)

To all whom it may concern:

Be it known that I, Jules Nisenson, a citizen of the United States of America, residing in the Borough of Manhattan, city of New York, county of New York, and State of New York, have invented a new, original, and ornamental Design for an Electric Barbecue Roaster or Similar Article, of which the following is a specification, reference being had to the accompanying drawing, forming part thereof.

Figure 1 is a front view in perspective of an electric barbecue roaster or similar article showing my new design.

Figure 2 is a rear view in perspective of the roaster of Figure 1 with the cover in an extended position thereof.

I claim:

The ornamental design for an electric barbecue roaster or similar article, as shown.

JULES NISENSON.
